ROLLER CONVEYER

Emile Piquerez, St. Cloud, France

Application October 23, 1935, Serial No. 46,438
In France October 31, 1934

7 Claims. (Cl. 104—135)

I have made applications for patents in France, filed the 31st October 1934 and in Great Britain filed the 27th March 1935.

The present invention relates to apparatus for transporting loads, in which a series of rollers with horizontal axles are driven mechanically and are rotated about their axles in such a way as to transport the loads deposited upon their upper surfaces.

10 The invention relates more particularly to apparatus of the above type used for transporting vehicles, and especially automobile vehicles, in washing and servicing installations.

15 The improved apparatus forming the subject of this invention preferably comprises two parallel horizontal conveyers, one receiving the right-hand wheels and the other the left-hand wheels of the vehicle, the length of the conveyers being such that the successive operations of cleaning, 20 drying or other services can be effected during the displacement of the vehicle from one extremity to the other of the conveyer.

According to the present invention the conveying apparatus is characterized by the following 25 features alone or in combination, viz:

Each roller included in the conveyer has a sprocket fixed thereto and all the sprockets of the same conveyer are driven by a single chain, the driving part of which engages with all the 30 sprockets.

The chain returns from the sprockets of the end rollers, in such a way that the slack return reach of the chain does not engage with the sprockets of the intermediate rollers.

35 One of the end rollers is actuated by a motor means and drives the working chain in such a direction that the upper stretch of the chain drives the other rollers.

Guiding elements are disposed above each pinion and impose on the chain a slightly curved course in such a way that it engages with several teeth of the same pinion.

A tensioning device is arranged on the slack part of the chain.

45 Each set of rollers is arranged between two longitudinal beams supporting bearings for the roller axles. The rollers are integral with their respective axles which turn in the bearings, and pass through and extend outwardly beyond at least one of the said beams. The portions of the axles outside the beam are each provided with a driving sprocket.

The chain and the various sprockets are enclosed by a water-tight casing.

55 The conveyer is prolonged by a non-working

part, in which the rollers are free on their axles, that is, are not driven and on which the vehicles come to a stop.

The rollers of the non-working part of the conveyer are provided with a braking arrangement to prevent their turning backwards in such a way as to react against the starting torque of the driven wheels of the vehicle and allow the latter to leave the apparatus under its own power.

When the conveyer is applied to a cleaning 10 installation the spacing of the roller axles in the direction of the longitudinal axes of the conveyer is at least equal to one and a half times the diameter of the rollers, whereby by its passage over the rollers, the vehicle undergoes numerous vertical shakings which facilitate the removal of mud and washing water from the vehicle.

Other characteristic features of the invention will appear in the course of the following description of a conveying apparatus in accordance with 20 the invention, said apparatus being shown on the annexed drawings, whereon:—

Fig. 1 is a diagrammatic elevation of the whole of the apparatus;

Fig. 2 is a plan view corresponding to Fig. 1;

Fig. 3 is an axial section of a roller;

Fig. 4 is a view in elevation of a part of the driving chain for the rollers;

Fig. 5 is an end view of the stopping arrangement for a roller of the non-working part of the 30 apparatus;

Fig. 6 is a view in elevation of a hanger for the chain; and

Fig. 7 is a section along the line A—A in Fig. 6.

Referring to the drawings:—

The apparatus comprises two conveyers having the same number of rollers and the same mechanical contrivances, the two conveyers being symmetrical with respect to the central plane of the installation.

40 One of these conveyers is formed by two longitudinal beams 1 and 2, one being situated at the side of the central plane and which will be called the "internal beam", the other beam 2 being called the "external beam". Each of the beams rests at its extremities on supports 3 and 4 and on any desired number of intermediate supports (not shown).

45 Between the two beams are disposed the rollers 5, Fig. 3, each fixed by pointed screws 6 to a shaft 7, the extremities of which pass through the webs of the beams and turn in supporting bearings in housings 8 and 9 fixed on the opposite faces of the webs of the beams.

50 The housing 8 on the internal beam 1 comprises

a ball bearing 10 held on to the shaft 7 by a nut 11, said housing being closed by a cap 12, whilst a packing washer 13 assures the water-tightness of the end of the shaft. In order to avoid any entry of water into the said housing, a plate 14 is mounted on the shaft and turns freely in a chamber which is open at its lower part.

On the external beam 2, the housing 9 also comprises a ball bearing and the same elements 10 for producing water-tightness as for the housing 8, but the end of the shaft 7 protrudes from the housing and carries a sprocket 15 shaped in such a way as to engage with the rollers of a sprocket chain 16.

15 The driving part of the chain passes successively over all the sprockets with which it engages, whilst the slack reach 16b of the chain slides on a rail 17 fixed on the inner face of the lower flange of the beam 2. Guides 18, arranged 20 at long intervals apart, keep the chain on the rail 17 and prevent it falling from it, particularly during mounting and dismounting operations.

The driving part 16 of the chain is kept in 25 engagement with the sprockets 15 by fixed guides 19, Figs. 3 and 4, arranged on the extensions 20 of the housing 9. The guides are slightly inclined in such a way as to cause the chain to follow a curvilinear path and to engage with several teeth of each sprocket. The guides 19 are also of symmetrical form with respect to their axes, so as to be capable of being turned around when they are worn on one side. As shown in Fig. 3 the guides 19 engage the rollers of the 35 sprocket chain 16, so that only rolling friction therebetween is developed. The thickness and the position of the guides are such that they bear only against the rollers with which the pintles of the chain are provided, in such a way that the 40 friction upon the guides may mainly be rolling friction.

The roller 5a which, see Fig. 1, is located at 45 one extremity of the conveyer is placed at a lower level than that of the other rollers so that the slack of the chain returned on the sprocket of this roller rests on the guide rail 17 without re-engaging with the sprockets 15. In order to 50 permit the driving of vehicles on to the conveyer, the extreme roller 5a is covered by a sheet iron plate 21 arranged at the level of the supporting surfaces of the running rollers 5.

At the opposite end of the conveyer, the roller 5b, over which the chain returns, serves to drive the chain, the axle of said roller being mounted 55 between the beams 1 and 2 and supported at its extremities by two ball-bearing housings identical with the housings 9, a sprocket 15b, identical with the running sprockets 15, being fixed at each end of the axle. A driving apparatus 22 60 constituted, for example, by an electric motor with a reduction gear which has a horizontal shaft 23 carrying two sprockets 24 drives the sprockets 15b through chains 25, and thus actuates the conveyer.

65 The slack parts of the chains 16 and 25 are provided with tension elements or stretchers 26 and 46.

Figs. 6 and 7 show in detail the stretcher 26, which comprises a saddle 27 slidable with little 70 friction between three vertical guides 28, 28a and 28b. The three guides are interconnected at their ends by heads 29 and 30, the former being fixed to the beam 2. A sprocket 31 is mounted on an axle 32 screwed into the saddle 27 between the guides 28 and 28a, this arrangement

allowing easy removal of the sprocket without having to dismount the guides. The slack of the chain 16b passes over the sprocket and can be tensioned by the action of a threaded rod 33 fixed to the saddle and passing through the lower head 30 on which it is supported by a tension screw 34 locked by a lock nut 35. The chain 16b leaves the sprocket of the roller 5b to pass on to the tensioning sprocket and a jockey sprocket leads it to the level of the return rail 17.

10 The tension device 46 is similar to the device 26 but is arranged horizontally under the beam 1, to which it is attached at its two extremities.

As the beams 2 are of U-form, the housings 9 and the chain 16 are accommodated within the 15 interior of its profile. A protecting casing 36, Fig. 3, is fixed between the two flanges of the beam and is held by ties 37 arranged between the sprockets. A water-tight joint 38 prevents the entry of water between the upper edge of 20 the casing and the flange of the beam.

The whole of the mechanical part for the driving and support of the rollers is thus well protected against water and mud, which is particularly important in the application of the 25 conveyer to cleaning installations for vehicles.

In such an application the installation is arranged in such a manner that the vehicles enter on to the conveyer at the extremity 5a opposite to the motor mechanism, the cleaning thus taking place on that part of the chain furthest from said mechanism. The draining of the water takes place at the central part of the conveyer and the drying and finishing operations are effected at the end where the tension devices and the driving system are arranged, so that all the mechanical elements which are not enclosed in a water-tight casing are at a substantial distance from the water and the mud.

The conveyer proper is prolonged at the discharging end by a non-working part formed by rollers 40, Fig. 1, mounted between the beams 1 and 2 and fixed to their axles, which turn in ball-bearing housings identical with the housings 8 and 9 of the working rollers.

45 For the rollers 40 the sprockets 15 are replaced by ratchet wheels 41, Fig. 5, each mounted in the same way at the end of the axles. Pawl 42 bears on the ratchet wheel and pivots on a pin 43 fixed on an extension 26 of the ball-bearing 50 housing 9. A spring 44 constantly urges the pawl 42 into contact with the wheel 41.

When the vehicle carried forward by the conveyer arrives on the non-working part of the conveyer it drives the rollers 40 and continues 55 to advance until the rear wheels of the vehicle are free of the roller 5b. At this moment, the vehicle is stopped. The bearing of the rollers on the pawls 42 allows the vehicle to move away 60 under its own power, the said rollers being unable to turn backwards under the action of the driving force of the wheels.

The conveyer thus formed can be utilized not only for the washing of vehicles but also in all 65 installations necessitating the transporting of these vehicles as, for example, installations for greasing the chassis when this operation is carried out as a continuous process.

It will be well understood that the apparatus could be adapted to its particular applications 70 and could undergo any modifications that are necessitated by such adaptations.

I claim:

1. Apparatus for transporting and supporting motor vehicles during servicing, comprising an 75

elongated conveyer having a plurality of rollers disposed parallel to each other, said rollers comprising a first group extending from the loading end of the conveyer toward the discharge end, 5 means for rotating the rollers of said first group forwardly for transporting the vehicles forwardly with their wheels locked, said first group extending the entire distance in which servicing of the vehicle is performed, a second group of rollers extending from the end of the first group to the 10 discharge end of the conveyer, for receiving the vehicles from the first group after the servicing operations with their wheels locked, the rollers of said second group being freely rotatable forwardly, means for preventing rearward rotation 15 of the rollers of said second group so that the vehicles may be removed from the discharge end of the said second group under their own power.

2. Apparatus for transporting motor vehicles 20 during servicing comprising a plurality of rollers, each roller being provided with a rotatable shaft on which it is fixed, a chain sprocket fixed on each shaft, a chain engaging by its driving reach with all the said sprockets, means for increasing the arc of engagement between the driving run 25 of the chain and each sprocket, means for tensioning the other reach of the chain and for keeping said other reach disengaged from the sprockets, and means for driving the shaft of 30 one of the end rollers in such a manner that the driving run is the upper reach of the chain.

3. Apparatus for transporting motor vehicles 35 during servicing comprising, a plurality of rollers arranged parallel with each other, each roller being provided with a rotatable shaft on which it is fixed, said rollers being arranged into two parallel rows, each row comprising, from the loading end to the discharge end, a first group 40 of rollers, each roller shaft of both first groups being provided with a sprocket wheel fixed thereon, a pair of chains each engaging with all of the sprocket wheels of one row of rollers, means disposed at the forward end of each of said first 45 groups to drive one of the rollers thereof, each row of rollers also comprising a group of non-driven rollers following the driven groups, the non-driven rollers being freely rotatable forwardly, means for locking the non-driven rollers against rotation from front to rear, the non- 50 driven groups of rollers extending over a length sufficient to receive a vehicle after servicing treatment, so that the latter may leave the apparatus under its own power.

4. Apparatus for transporting motor vehicles 55 during servicing, comprising a plurality of rollers arranged in two parallel rows, each roller having a rotatable shaft on which it is fixed, a sprocket wheel on each shaft, a chain engaging with its driving reach with all the roller sprocket 60 wheels in the same row, a pair of parallel U-shaped beams, two bearings for supporting each roller shaft, each of said bearings being mounted in one of said U-shaped beams, the sprocket wheel of each roller being mounted at one end 65 of its shaft and in the groove of one of said U-shaped beams, plates for closing the grooves of said U-shaped beams to form casings, means including stuffing boxes providing water tightness of the casings, and a motor having a chain power 70 transmission for driving the shafts of one of the end rollers of each row.

5. Apparatus for supporting and transporting motor vehicles during servicing, comprising a plurality of rollers parallel with each other, and arranged in two parallel rows, each row comprising from loading to the discharge end a first 5 group of rollers, each having a rotatable axle provided at one end with a sprocket wheel, said roller axles having supporting bearings, and chains each engaging with all the roller sprocket wheels of one row, a motor having a shaft and a 10 chain transmitting driving force between the motor shaft and the shaft of the end roller sprocket wheel at the front end of each of said first groups of rollers, each of said rows of rollers also comprising a second group of non-driven 15 rollers arranged following the driven rollers, said second groups of non-driven rollers extending over a length sufficient to receive a vehicle after servicing, means for locking the non-driven rollers against rotation in the direction from front 20 to rear, said non-driven rollers being freely rotatable forwardly, so that the vehicle with its wheels locked can pass onto said non-driven rollers without sliding and may leave the apparatus under its own power, and a pair of U-shaped 25 supporting beams at the ends of the rollers of each row, the bearings, sprocket wheels, driving chains and locking means being disposed in the grooves of said beams, plates closing said grooves 30 to form water tight casings and stuffing boxes for 35 excluding water and dirt from the bearings.

6. Apparatus for supporting and transporting motor vehicles during servicing, comprising a plurality of parallelly disposed rollers arranged 35 in two parallel rows, the axes of the rollers being transverse to the direction of extent of the rows, each roller having a rotatable shaft on which it is fixed, each shaft having a pair of bearings on which it is mounted, one at each end thereof, each bearing being enclosed in a casing and 40 means for excluding water and solid matter from said casings, a sprocket wheel on each shaft, a pair of chains each engaging with its driving reach all the sprocket wheels of the rollers in 45 one of the rows, the distance between the axes of the rollers in the direction of the rows being substantially equal to one and a half times the diameter of a roller, and means for driving the shaft of one of the end rollers of each row so that 50 the driving reaches of the chains are the upper reaches thereof.

7. Apparatus for transporting motor vehicles 55 during servicing comprising a plurality of rollers, each roller being provided with a rotatable shaft on which it is fixed, a sprocket fixed on each shaft, a sprocket chain having rollers engaged by its driving reach with all the sprockets, means comprising fixed inclined guides extending downwardly at an angle between each adjacent pair 60 of sprockets and engaging the rollers of the chain for increasing the arc of engagement between the driving run of the chain and each sprocket, means for tensioning the other reach of the chain and for keeping said other reach disengaged from the sprockets, and means for driving the shaft of one of the end rollers in such a manner that the driving run is the upper reach 65 of the chain.

EMILE PIQUEREZ.
